PAPERBOARD FLUID CONTAINER

Richard Sisco, 470 Knollwood Road, Ridgewood, N.J.

Filed Feb. 15, 1958, Ser. No. 780,351

5 Claims. (Cl. 222—566)

My invention relates to a paperboard fluid container and more particularly to an improved paperboard container which may be employed as a milk carton which carton can be used with standard filling and bottling equipment designed for use with glass bottles.

Containers made of paperboard, cardboard, strawboard, pasteboard, or the like are currently replacing glass bottles for distribution of milk to stores, homes, institutions, and coin-controlled merchandising machines.

These paperboard containers of the prior art cannot be filled by standard bottling equipment, nor can they be used with standard crimpable caps or snap caps which are used with glass bottles.

Glass bottles are expensive and must be replaced after an average use of six or seven times. They must be collected, handled, cleaned, and sterilized. They cannot be used in vending machines since they are apt to become broken in the delivery arrangements customarily found in these.

In my copending application, Serial No. 775,969, filed November 24, 1958, for a Cardboard Milk Container, I have shown one construction adapted to overcome the disadvantages of the prior art. That application contemplates a folding paperboard construction having a reinforcing member adapted to be assembled in the container in nested relation with a truncated pyramid top.

The instant case instead of having the reinforcing member formed of a separate member adapted to be nested with the top has the reinforcing element formed integrally with the remainder of the container.

One object of my invention is to provide a paperboard container which can be used with standard bottling equipment designed for use with glass bottles so that my improved paperboard fluid container may be filled automatically.

Another object of my invention is to provide a paperboard container for milk or other liquids which can withstand the pressure required for capping the paperboard container with capping machines designed for use with glass bottles.

Another object of my invention is to provide a paperboard container for liquids having a top in the form of a truncated pyramid which top is reinforced by a reinforcing member formed integrally with the paper blank from which the paperboard container is formed.

Other and further objects will appear from the following description:

In general my invention contemplates the provision of a paperboard container folded from a single blank, which container is formed with a reinforced top. My container is formed with a square cross-sectional area having the top in the form of a truncated square pyramid. The pyramid top is reinforced by providing an extended area of double thicknesses of paper adapted to transfer pressure from the top to the corners of the side walls of the container.

In the accompanying drawings which form part of the instant specification and which are to be read in con-

2

junction therewith and in which like reference numerals are used to indicate like parts in the various views:

Figure 1 is a perspective view of a paperboard container for liquids such as milk or the like containing one embodiment of my invention.

Figure 2 is a plan view of a blank which is adapted to be folded to form the container shown in Figure 1.

Figure 3 is a sectional elevation with parts broken away of the container shown in Figure 1 drawn on an enlarged scale.

Figure 4 is a fragmentary perspective view showing the top of my container in partially folded condition drawn on an enlarged scale.

Figure 5 is a sectional view drawn on a smaller scale viewed along the line 5—5 of Figure 3.

More particularly, referring now to the drawings, I form my container of any appropriate fibrous material such as paperboard, pasteboard, cardboard, strawboard, boxboard, juteboard, or the like. For purposes of convenience, I shall refer to this material as "paperboard" hereafter in the specification and claims. The thickness of the paperboard stock will depend, of course, on the size of the container which I desire to make.

Referring now to Figure 2, the blank indicated generally by the reference numeral 10 is stamped out of a single piece of paperboard by an appropriate die. The panels 12, 14, 16, and 18 form the sides of the container. The tab 20 is adapted to be secured to the inside of the right-hand edge of the panel 12 by any suitable adhesive known to the art. Preferably, I employ an adhesive of the chemically processed starch type which is insoluble and nontoxic.

The bottom tabs 22, 24, 26, and 28 are adapted to be folded over into a bottom which will be described more fully hereinafter. It will be understood, of course, that the bottom structure shown in my copending application, Serial No. 775,969, mentioned above, may be employed if desired.

The upper side of panel 12 is formed with tab 30 to which is attached three ears 32, 34, and 36. Ear 32 is adapted to be folded along line 33. Ear 34 is adapted to be folded along line 35, and ear 36 is adapted to be folded along line 37. The tab 30 is adapted to be folded along line 31. Ear 36 is provided with a pair of extensions 38 and 40. Extension 38 is adapted to be folded along line 39 and extension 40 is adapted to be folded along line 41.

Panel 14 is provided with a tab 50 adapted to be folded along line 51. The tab 50 is provided with ears 52, 54, and 56. The ear 56 is provided with a pair of extensions 58 and 60. Ear 52 is adapted to be folded along line 53. Ear 54 is adapted to be folded along line 55. Ear 56 is adapted to be folded along line 57. Extensions 58 and 60 are adapted to be folded along lines 59 and 61 respectively. It will be observed that the tab 56 is provided with a circular opening 62. This opening is adapted to receive the pouring spout which may be formed as shown in my copending application, or molded of polyethylene plastic or any other suitable resinous material.

The panel 16 is provided with a tab 70 adapted to be folded along line 71. The tab 70 is provided with three ears 72, 74, and 76. These ears are adapted to be folded along fold lines 73, 75, and 77 respectively. The ear 76 is provided with a pair of extensions 78 and 80 adapted to be folded along lines 79 and 81 respectively.

It will be observed that the tabs 30 and 70 and their ears are symmetrical. The two semicircular portions of ears 36 and 76 are adapted when folded to form a single circular opening aligned with the opening 62.

Attached to panel 18 along fold line 89 is tab 88. The tab 88 is provided with three ears 82, 84, and 86, which ears are adapted to be folded along fold lines 83,

85, and 87 respectively. The tab 86 is provided with a circular opening 92 which corresponds to the circular opening 62. The tab 86, however is provided with no extensions.

The width of the panels 12, 14, 16, and 18 is the same for each, thus providing a container having a square cross-sectional area when folded.

Referring now to Figure 4, after the tab 20 has been glued to the edge of panel 12, the tabs 70 and 30 are folded toward each other as shown in Figure 4. The ears 76 and 36 are adapted to abut. The extensions 40 and 78 and the extensions 38 and 80 are folded down and likewise abut. The ears 72 and 74 of tab 70 abut the edges of extensions 78 and 80. Similarly, the ears 34 and 32 of tab 30 abut the edges of extensions 38 and 40 of tab 36. The arrangement of parts and the dimensions of the parts are such as to accomplish this and the parts will occupy the position shown in Figure 4. If desired, a mandrel or folding form may be employed over which the parts may be folded readily, as will be understood by those skilled in the art.

With the tabs 30 and 70 and their ears and extensions in the position shown in Figure 4, an adhesive is applied to the underside of tabs 50 and 88 and their ears and extensions, as indicated in Figure 4. The shape and size of the area formed by ears 34 and 72 and extensions 40 and 78 is such that it will occupy the major portion of the area of tab 88. The fold line 73 will coincide with the fold line 85 and the fold line 33 will coincide with the fold line 83. The tab 86 will exactly cover the area formed by tabs 36 and 76 and the opening 92 will coincide with the opening formed by the two semicircular portions formed in tabs 36 and 76.

After tab 88 has been folded over, the ear 84 will be adhesively secured to the outside of tab 70 and the ear 82 will be adhesively secured to the outside of tab 30. The parts are now in position to complete the assembly of the top of the container. The tab 50 is folded over the assembly of tab 74, extension 80, extension 38 and tab 32. This assembly will occupy a substantial portion of the area of tab 50. The underside of tab 56 will cover the upper side of tab 86 and opening 62 will be in alignment with opening 92. The ear 52 will occupy a portion of tab 70 symmetrical with ear 84. Similarly, the ear 56 will occupy a portion of tab 30 symmetrical with ear 82. The extension 58 will be adhered to tab 70 in abutting relation with ears 84 and 52. The arrangement of parts will be that shown in Figure 1. The dimensions of the parts are such that there will be a bridging across the complete width of tab 70.

In a similar manner, ear 54 will be adhered to the exterior of tab 30 symmetrical with ear 82. The extension 66 will occupy a position abutting the edges of ears 54 and 82 in adhering relation to the exterior of tab 30. The arrangement will be symmetrical to that formed by ears 84 and 52 and extension 58.

The symmetry of the arrangement can readily be seen by reference to Figure 5 in which the dotted lines show the position of tabs and extensions on the exterior of the container and the full lines show the position of tabs and the extensions in the interior of the container. It will be observed that all four sides of the pyramid top of the container are formed with substantially two thicknesses of material and that the horizontal top of the container is formed with three thicknesses of material. I have, thus in effect, provided the top of my container with the equivalent of a reinforcing insert which is provided for in my copending application by a separate member.

After the top of the container has been formed, the folding mandrel, if used, is removed and the bottom of the container may then be formed as shown in my copending application.

The preferred form of bottom for the instant con-

tainer, however, is that shown in Figure 3. The four bottom tabs 22, 24, 26 and 28 are folded inwardly at right angles to the panels to which they are attached and a square of polyethylene, 100, is placed over the four bottom tabs. A square of paperboard bottom, 102, is then placed over the polyethylene layer 100 and the assembly heat-sealed, that is, the four bottom tabs and the bottom form the outer layers of a sandwich between which a portion of the polyethylene bottom 100 is embraced therebetween. The particular mode of heat-sealing the container bottom 102 to the bottom tabs 22, 24, 26, and 28 is not part of my invention but is shown in the interest of completeness.

After the container has been formed as indicated above, it is immersed so that a layer of paraffin is provided over the container walls both interior and exterior. Referring now to Figure 3, the exterior layer of paraffin is indicated by the reference numeral 104 and the interior layer of paraffin wax is indicated by the reference numeral 106. The coating of the container with paraffin wax is well understood by those skilled in the art. This is usually accomplished by immersing the entire container into a bath of molten paraffin wax maintained at a temperature between 170° F. and 180° F. The container is removed from the bath, the excess paraffin drained, and then the container is chilled at a temperature in the vicinity of 40° F. to set the wax impregnation.

After the container has been coated, a plastic pouring spout 108, shown in Figure 3, is snapped into place. It is understood, of course, that this pouring spout may be of any suitable material and may be inserted before the wax impregnation if desired.

It will be seen that I have accomplished the objects of my invention. My container is formed from a single sheet 35 of paperboard material which is adapted to be folded to form a container having a top in the form of a truncated square pyramid. The pyramid is reinforced with a plurality of layers of paperboard which are formed integrally from the blank. I am enabled in this manner to obtain 40 a reinforced top without the use of a separate nesting reinforcing member. I am thus able to produce a paperboard container for liquids which can be employed with the standard filling and capping machinery now used customarily for glass bottles.

It will be understood that certain features and subcombinations are of utility and may be employed without reference to other features and subcombinations. This is contemplated by and is within the scope of my claims. It is further obvious that various changes may be made in 50 details within the scope of my claims without departing from the spirit of my invention. It is therefore to be understood that my invention is not to be limited to the specific details shown and described.

Having thus described my invention, what I claim is:

1. A paperboard container for liquids including in combination a single sheet of paperboard material folded to provide the side walls and top of a container, said top having the form of a truncated square pyramid, said sheet comprising four rectangular panels of similar shape 55 folded to form said side walls, tabs having generally the shape of truncated triangles extending upwardly from each of said panels to form the sides of said truncated square pyramid, generally triangularly-shaped ears extending from each of the sides of each of said truncated triangular tabs, generally rectangular ears extending from the line of truncation of two alternate truncated triangular tabs, said rectangular ears being formed with notches, one of said rectangular ears being formed with a pair of lateral extensions, generally square ears extending from the line of truncation of the other pair of alternate truncated tabs, each of said square ears being formed with an opening symmetrical with the pair of said notches, one of said square ears being formed with a pair of 60 lateral extensions, said notches and said openings being 65

in aligned position, and a pouring spout positioned in said aligned openings.

2. A paperboard container for liquids including in combination a single sheet of paperboard material folded to provide the side walls and top of a container, said top having the form of a truncated square pyramid, said sheet comprising four rectangular panels of similar shape folded to form said side walls, an integral laterally extending tab attached to an outer of said rectangular panels adapted to be adhered to the other outer of said rectangular panels to form a body section of substantially square cross-sectional shape, tabs having generally the shape of truncated triangles extending upwardly from each of said panels to form the sides of said truncated square pyramid, generally triangularly-shaped ears extending from each of the sides of each of said truncated triangular tabs, generally rectangular ears extending from the line of truncation of two alternate truncated triangular tabs, said rectangular ears being formed with notches, each of said rectangular ears being formed with a pair of lateral extensions, generally square ears extending from the line of truncation of the other pair of alternate truncated tabs, each of said square ears being formed with an opening symmetrical with the pair of said notches, one of said square ears being formed with a pair of lateral extensions, said notches and said openings being in aligned position, and a pouring spout positioned in said aligned openings.

3. A paperboard container for liquids including in combination a single sheet of paperboard material folded to provide the side walls and top of a container, said top having the form of a truncated square pyramid, said sheet comprising four rectangular panels of similar shape folded to form said side walls, an integral laterally extending tab attached to an outer of said rectangular panels adapted to be adhered to the other outer of said rectangular panels to form a body section of substantially square cross-sectional shape when said sheet is folded, tabs extending from the bottom of each of said panels adapted to form part of the bottom portion of said container, tabs having generally the shape of truncated triangles extending upwardly from each of said panels to form the sides of said truncated square pyramid, generally triangularly-shaped ears extending from each of the sides of each of said truncated triangular tabs, generally rectangular ears extending from the line of truncation of two alternate truncated triangular tabs, said rectangular ears being formed with notches, each of said rectangular ears being formed with a pair of lateral extensions, generally square ears extending from the line of truncation of the other pair of alternate truncated tabs, each of said square ears being formed with an opening symmetrical with the pair of said notches, one of said square ears being formed with a pair of lateral extensions, said notches and said openings being in aligned position, and a pouring spout positioned in said aligned openings.

4. A paperboard container for liquids including in combination a single sheet of paperboard material folded

to provide the side walls and top of a container, said top having the form of a truncated square pyramid, said sheet comprising four rectangular panels of similar shape folded to form said side walls, an integral laterally extending tab attached to an outer of said rectangular panels adapted to be adhered to the other outer of said rectangular panels when said sheet is folded to form a body section of substantially square cross-sectional shape, tabs extending from the bottom of each of said panels adapted to form part of the bottom portion of said container, a separate square paperboard member adapted to coact with said bottom tabs to form the container bottom, tabs having generally the shape of truncated triangles extending upwardly from each of said panels to form the sides of said truncated square pyramid, generally triangularly-shaped ears extending from each of the sides of each of said truncated triangular tabs, generally rectangular ears extending from the line of truncation of two alternate truncated triangular tabs, said rectangular ears being formed with notches, each of said rectangular ears being formed with a pair of lateral extensions, generally square ears extending from the line of truncation of the other pair of alternate truncated tabs, each of said square ears being formed with an opening symmetrical with the pair of said notches, one of said square ears being formed with a pair of lateral extensions, said notches and said openings being in aligned position, and a pouring spout positioned in said aligned openings.

5. A paperboard container blank including in combination a single sheet of paperboard material having four rectangular panels of similar shape adapted to form the sides of the container, tabs having generally the shape of truncated triangles extending upwardly from each of said panels, generally triangularly shaped ears extending outwardly from each of the sides of each of said truncated triangular tabs, generally rectangular ears extending upwardly from the line of truncation of two alternate truncated triangular tabs, said rectangular ears being formed with notches, one of said rectangular ears being formed with a pair of lateral extensions, generally square ears extending upwardly from the line of truncation of the other pair of alternate truncated tabs, each of said square ears being formed with an opening symmetrical with said pair of notches and one of said square ears being formed with a pair of lateral extensions.
